UNITED STATES PATENT OFFICE.

MIKE STAUDOHAR, OF GIRARD, OHIO.

DESIGN FOR A COMBINED TABLE AND CHAIR.

Application filed February 16, 1922. Serial No. 729. Term of patent 7 years.

To all whom it may concern:

Be it known that I, MIKE STAUDOHAR, a citizen of Yugoslavia, residing at Girard, in the county of Trumbull and State of Ohio, have invented a new, original, and ornamental Design for Combined Table and Chairs, of which the following is a specification, reference being had to the accompanying drawing, forming part thereof.

I claim:

The ornamental design for a combined table and chair, as shown.

MIKE STAUDOHAR.
